UNITED STATES PATENT OFFICE.

EZRA W. VANDUZEN, OF CINCINNATI, OHIO.

IMPROVED MODE OF HANGING BELLS.

Specification forming part of Letters Patent No. 59,098, dated October 23, 1866.

To all whom it may concern:

Be it known that I, EZRA W. VANDUZEN, of Cincinnati, Hamilton county, Ohio, have invented a new and useful Improvement in Hanging Bells; and I do hereby declare the following to be a full, clear, and exact description thereof, reference being had to the accompanying drawing, making part of this specification.

This invention relates to the class of large bells which are rung by swing of the bell itself; and consists in a construction of the bell proper, and of the hanger or yoke which substitutes for the customary costly and bulky crown loops a single large aperture, of sufficient capacity for the passage of all the bolts which unite the bell to the yoke, so as to permit a circumferential adjustment of the bell proper without detaching it from the yoke.

The accompanying drawing is an axial section of a bell embodying my invention.

The yoke C has a flange or collar, D, between which and a crown-plate, E, that portion of the bell immediately surrounding the aperture B is firmly gripped on the tightening of two or more bolts, F F' G G', which traverse both yoke and crown-plate. Two of these bolts, F F', serve, in conjunction with caps H H', also to hold the two springs or buffers I I', either of which may be independently released or inserted by the relaxing and tightening of its appropriate bolt F or F', without unhang-ing or disturbing the bell.

The cheeks or spade-handle K, by which the clapper is suspended, may be a cast pro-jection from the under side of the crown-plate E.

The above bell-hanging device possesses over all others known to the undersigned several decided practical advantages, viz: Iron is made to take the place of a large mass of costly bell-metal which constitutes the crown portion of a customary bell. The bell is more easily molded and cast, and is less

liable to crack from unequal contraction in cooling than is one with a solid crown.

The grip of the yoke and crown-plate upon the margins of the aperture B is necessarily at such a radial distance as to insure a firm and retentive hold and bearing, not liable to displacement nor undue strain in the act of swinging the bell.

The bell proper may at any moment be shifted circumferentially, so as to present an unworn point of impact to the clapper, by simply slackening the bolts, thus prolonging the durability of the bell.

The above-described construction is partic-ularly designed for bells of four hundred pounds weight and upward, employing more than one connecting-bolt.

I claim herein as new and of my inven-tion—

1. A bell proper, having a crown opening, B, in combination with a yoke and crown-plate, substantially as and for the purposes set forth.

2. The arrangement of flanged or collared yoke C D, perforated crown-plate E, and two or more attaching-bolts, F F' G G', for com-bination with an open-crowned bell, substan-tially as set forth.

3. In the described combination, the crown-plate E, attaching-bolts F F' and caps H H', for the purposes stated.

4. The crown-plate E, having a cast projec-tion or spade-handle, K, for the clapper, as and for the purpose set forth.

5. The perforated crown-plate E, in the de-scribed combination, with two or more attaching-bolts, F F', as and for the purpose set forth.

In testimony of which invention I hereunto set my hand.

E. W. VANDUZEN.
